UNITED STATES PATENT OFFICE.

JOHN F. O'CONNOR, OF CHICAGO, ILLINOIS, ASSIGNOR TO WILLIAM H. MINER, OF CHAZY, NEW YORK.

HIGH-CAPACITY SPRING.

Application filed February 16, 1921. Serial No. 445,292.

To all whom it may concern:

Be it known that I, JOHN F. O'CONNOR, a citizen of the United States, residing at Chicago, in the county of Cook and State 5 of Illinois, have invented a certain new and useful Improvement in High-Capacity Springs, of which the following is a full, clear, concise, and exact description, reference being had to the accompanying drawings, forming a part of this specification.

This invention relates to improvements in high capacity springs.

In shock absorbing devices of high capacity, as for instance, railway draft riggings, it is the general practice to employ either alone or in combination with friction creating elements, a heavy spring. Heretofore, these springs, which are made of relatively large diameter rods, have been 20 formed at their ends with so-called tapered flanges in order to provide flat bearing seats at the ends of the spring. In manufacturing such springs, it is first necessary that the ends of the rod before coiling be ham-

25 mered or forged to provide the tapered tangs and in coiling the rods, the forward ends must first be clamped in proper position and the rear ends of the rods held by tongs in the hands of the operator who is required 30 to exert great strength in preventing the rods from twisting to insure that the rear tang retains its proper position in the finished coiled spring. Experience has shown that much waste is entailed in manufacturing 35 springs of this character due to the human element entering into the coiling thereof, the operators frequently becoming fatigued after a few hours' work and unable to maintain the position of the rear 40 tang with the result that many of the coils must either be rejected or subsequently ground to provide the flat bearings.

It is also a well known fact that in the ordinary helically coiled spring, the capacity 45 of a spring having a plurality of continuous coils is no greater than that of a single turn or coil of 360° , assuming the same diameters of rods, same pitch and same diameters of the coils. Where such springs 50 of multiple continuous coils are employed in a friction draft gear, for instance, the total capacity of the spring provides only a relatively small proportion of the total capacity of the friction draft gear, the 55 major portion of the capacity being neces-

sarily imposed upon the friction elements. Where such springs are employed without friction elements in draft gears, the capacities are limited because of the small space allowed for the draft gears on railway cars. 60 Furthermore, when heavy springs having tapered tangs, as above described, are employed it is a well known fact that more than a complete coil of the spring remains inactive or dead and the movement of the 65 spring decreased to that extent.

One object of my invention is to provide a spring suitable for heavy duty—as for instance in railway draft gears, which may be used either alone or in combination with 70 friction elements and wherein the cost of manufacture is materially reduced as compared to present practice; wherein the accuracy of results is increased, the total capacity of the complete spring multiplied as 75 compared with the usual commercial continuous helical springs; and wherein the full length of the rod material employed is utilized.

More specifically, the object of my invention is to provide a high capacity spring composed of a number of separate spring coils, each having squared off ends and wherein the total capacity is multiplied as 80 compared with a spring of continuous helical formation, the arrangement being such that an adequate compression stroke or movement is also obtained.

In the drawing forming a part of this specification, I have illustrated my improvements in connection with a railway draft rigging and in said drawing, Figure 1 is a horizontal, longitudinal, sectional view of a portion of a railway draft rigging showing my improvements in connection therewith, 90 all of the parts being shown in their normal or full release position. Figure 2 is a vertical, transverse, sectional view corresponding to the line 2—2 of Figure 1. Figure 3 is an elevational view of one of the 95 improved spring caps employed with my construction, Figure 4 is a detached enlarged elevational view of one end of the spring shown in Figure 1 and illustrating the positions assumed by the spring and 100 cap when the spring is under full compression. And Figure 5 is a view corresponding to Figure 1 illustrating a somewhat 105 different embodiment of the invention.

In said drawing, and referring first to the 110

construction illustrated in Figures 1 to 4, 10—10 denote channel draft sills of a railway car to the inner faces of which are secured front stop lugs 11 and rear stop lugs 12. The inner end of a drawbar is indicated at 13, the same being operatively associated with the shock absorbing device proper by means of a hooded cast yoke 14 and coupler key 15. The improved spring is mounted 10 within the yoke 14 and at the ends of the spring are provided a front main follower 16 and rear main follower 17. The yoke and parts contained therein are supported by a detachable saddle plate 18.

15 In carrying out my invention I employ four like units A—A, the same being superimposed one upon the other in axial alinement. Each of said units A is coiled to the desired helical pitch greater than the diameter of coil-forming rod and extends thru two complete circles or 720° . The ends of the units A are squared off or flat as indicated at 19 and 20 in planes perpendicular to the axis of the coil-forming rods.

25 In view of the fact that all of the units A are of like construction and pitch, it is evident that any two adjacent units will be in line contact throughout an arc of 360° and the end 19 of one unit will partly overlap 30 the opposite end 20 of the next adjacent unit. With this construction, I obtain double the capacity that would be obtained from a continuous helical coil having a plurality of turns of the same pitch, coil diameter and 35 same material. The compression stroke where four units A are employed as shown, is five times the movement or compression stroke of a single complete turn of same pitch. In actual practice, I will preferably 40 employ an inner nested series of coil units B as best shown in Figure 2, of similar construction and having the same total compression stroke, the end units of the inner series fitting over studs 21—21 formed on 45 the inner sides of the followers 16 and 17 in order to center the spring. Preferably I also employ an outer tube or casing 22 to prevent displacement of any of the units, the length of said casing corresponding to 50 the solid height of the complete spring.

It is desirable in heavy duty springs of the type disclosed in this application to have a flat bearing on the followers and to that end I provide novel spring caps designated 55 generally by the references C—C. Said caps are of like construction and each extends thru an arc of approximately 270° , as clearly indicated in Figure 3. On the side adapted to engage with a follower, the cap 60 has a flat bearing surface 23 in the same plane throughout. On its inner side adapted to engage with a spring unit, the cap C is formed with a helical surface 24 arranged to conform to the pitch of the spring coils 65 when the latter are in their fully compressed

or closed condition. At the thicker end of the annular cap C, a flat face 25 is provided adapted to engage with a corresponding end 20 or 19 on one of the units A and the dimension of the thicker end of the cap C, taken parallel to its face 25 corresponds to the diameter of the rod used in forming the units A. With this arrangement, as best shown in Figure 4, when the spring is compressed solid, the cap C will 70 lie flat against the corresponding follower on the one side and will provide a continuous true line bearing thru an arc of approximately 270° with the end turn of the adjacent unit A. When the spring as 75 an entirety is extended, the caps C may tilt bodily to positions substantially as shown in Figure 1.

Not only do I obtain the multiplied capacity as above described, but also it will be 80 evident that the coil units may be made in a very simple manner since each can be formed directly by machinery from rods cut to proper length without the necessity of forging the ends or of holding the rods as 85 the same are coiled in a machine.

In the construction illustrated in Figure 5, I employ two like units D—D and a unit E. Each of the units D extends thru an arc of approximately 360° and has squared off 90 ends 120—119 so that, when the two units D—D are assembled in axial alinement, they will be in line contact throughout the full arc of approximately 360° . The unit E, as shown, extends thru six complete turns and 100 is of the same pitch, same coil diameter and same rod diameter as the units D—D. The ends of the units E are also squared off or left flat as indicated at 220 and 219. At the end adjacent the units D, it is evident 105 the unit E will be in full line contact throughout an arc of approximately 360° with the next adjacent unit D. Spring caps C—C' are employed similar to those referenced C in the other construction.

With the arrangement shown in Figure 5, I obtain a capacity equal to three times the capacity of either one of the units D or E and a total movement or compression stroke equal to six times the movement of 110 a single turn coil.

I have herein shown and described what I now consider the preferred manner of carrying out my invention but, as will be evident to those skilled in the art, various 115 changes and modifications may be made without departing from the spirit of the invention, among such changes being any desired combination of units such as shown in either Figure 1 or 5 and by which may 120 be obtained the desired capacity with the desired compression stroke. All such changes and modifications are contemplated as come within the scope of the claims appended hereto.

I claim:

1. A high capacity spring comprising: a plurality of helically coiled rod units arranged in axial alinement in abutting relation, the units being of the same pitch and having each flat ends extending in planes substantially perpendicular to the axis of the coil-forming rod, the effective pitch being greater than the diameter of the 10 coil-forming rod and adjacent units having their coils in line contact thru arcs of substantially 360° .

2. A high capacity spring comprising: a plurality of helically coiled rod units in abutting relation and in axial alinement, the units being of the same pitch and having each flat ends extending in planes substantially perpendicular to the axis of the coil-forming rod, the effective pitch being greater than the diameter of the coil-forming rod and adjacent units having their coils in line contact thru arcs of substantially 20

360° , one end of one unit abutting and partially overlapping the relatively opposite end of an adjacent unit.

25

3. A high capacity spring comprising: a plurality of helically coiled rod units in abutting relation and in axial alinement, the units being of the same pitch and having each flat ends extending in planes substantially perpendicular to the axis of the coil-forming rod, the effective pitch being greater than the diameter of the coil-forming rod and adjacent units having their coils in line contact thru arcs of substantially 360° , at least one of said units having more than a complete turn of 360° .
